UNITED STATES PATENT OFFICE.

OLOF FROBERG, OF BENTON HARBOR, MICHIGAN.

COLLAR AND CUFF STARCHER.

1,158,040.

Specification of Letters Patent.

Patented Oct. 26, 1915.

Application filed July 23, 1914. Serial No. 852,729.

To all whom it may concern:

Be it known that I, OLOF FROBERG, a citizen of the United States, residing at Benton Harbor, in the county of Berrien 5 and State of Michigan, have invented new and useful Improvements in Collar and Cuff Starchers, of which the following is a specification.

The invention has for an important object 10 to give a compact machine so constructed that it may be used simultaneously as a cuff and collar starcher and as a shirt starcher, without either operation interfering with the other, and at the same time 15 working with a high efficiency.

A further object is to give a desirable 20 conveying and delivering mechanism for handling collars, which will enable the tending of the machine as to the feeding and removal of collars and cuffs by one operator, with a minimum number of movements.

A purpose also is to present efficient 25 means for insuring the proper entry of starch into the body of collars and cuffs, operative to remove excess of starch, and adjustable to meet the conditions of various 30 grades of starch,—that is, thick, or thin, high grade or low grade.

It is an aim of the invention to enable 35 the same starch pan to be used both for shirts and to supply the starch for collars and cuffs, when desired.

Additional objects, advantages and features 40 of invention will appear, some of which will be at once apparent from the following description of the peculiar construction arrangement and combination of parts in the present embodiment of my invention, in the drawings of which—

Figure 1 is a side view of the invention, 45 Fig. 2 is a front view thereof, Fig. 3 is a sectional view, Fig. 4 is a transverse sectional detail showing the mounting and adjustment of the arm 35 and roller 85. Fig. 5 is a detail of means for lifting the roller 22.

There is illustrated a suitably mounted 50 starch box 10 with a steam chest 11 of ordinary construction in the lower part, and provided with the drain cock 12. At one side of the box there is mounted in a suitable manner the drive shaft 13 carrying the

loose and splined pulleys 14 and 15 receiving alternately the power belt 16, the shifting means for which is not shown and may 55 be of any familiar form. This shaft carries a small gear 17 meshed with two large gears 18 and 19, the former being carried on a stub shaft 20 mounted on the side of the box 10 while the second large gear is 60 carried by the shaft 21, journaled on the upper edges of the box and extending transversely thereacross near the front. On this shaft there is splined the large roller 22 the periphery of which is spaced suitably 65 from the adjacent end of the box to admit a small roller 23, with a clearance between the rollers, the latter roller being journaled in slots 24 formed in the edge of the box at 70 each side. At each side of the box adjacent the inner side of the large roller there are standards 25, extending some distance above 75 the roller and having horizontal arms 26 extended forwardly above the roller, stopping short of a vertical line from the front end of the box 10. The arms 26 carry at their outer ends the transverse apron roller 27. At the upper ends of the standards 25 there are vertical slotted guide brackets 28, in 80 each of which there is vertically movable the journal box 29 adjustable by the hand screw 30 threaded into the upper end of the bracket. In these boxes 29 there is journaled the adjusting roller 31. Immediately below these brackets slots 32 are formed in 85 the rear sides of the standards inclined downwardly toward their inner ends, and journaled in the slots there is a roller 33, the upper side of which is approximately on the level with the under side of the roller 27. 90

A transverse rod 34 is mounted across the box just below the roller 23, upon which are pivoted the outer ends of L-shaped arms 35, extending inwardly and downwardly beneath the large roller and thence upwardly, 95 being provided with interiorly threaded blocks 36 at their upper ends located over the sides of the box, through which are engaged the adjusting screws 37 bearing downwardly upon wear plates 38 on the box. 100 The lower ends of the arms are horizontally slotted as at 39, to allow limited movement on the rod. The lower portions of the arms 35 are formed with slots 40 opening up-

wardly, in which there are journaled two rollers 41, spaced a suitable distance apart and adapted to bear simultaneously against the large roller under adjustment of the 5 screw 37. A third roller 41' is mounted in suitable horizontal slots opening at the rear-most lower portion of the arms 35, located approximately in a vertical line with the roller 31 at the upper ends of the standards.

10 An endless apron belt 42 is engaged outwardly of the rollers 27, 29, 41', 41 and 23, extending under the large roller 22 and inwardly of the roller 33. A multiplicity of laterally spaced endless tapes 43 are engaged around the large roller and the roller 33, the tapes and apron being thus adapted to move together from the throat or receiving space 44 between the rollers 22 and 23, to the roller 33. Carried by the arms 26 at 15 the left and right sides respectively, there are brackets 45 and 46, the latter having suitable bearings 47 immediately below the level of the apron passing from the roller 33 to the roller 27. Two of the respective 20 brackets are on each arm, the first named brackets being slotted and having sliding journals 48 adjustable by screws 49 threaded into the brackets as shown. In the journals 47 and 48 rollers 50 are mounted, on 25 which an endless delivery apron 51 is stretched, the inner edge of which is closely adjacent the roller 33, whereby it may receive collars and cuffs passing over the last named roller. The right hand roller 50 30 (Fig. 2) is carried by a shaft 52, at the inner end of which there is secured a bevel gear 53 meshed with a larger bevel gear 54 at the end of a shaft 55, which may be the support for the roller 33. The roller 50 at 35 the left is located well outwardly of the arm 26 so that articles falling thereover will pass clear of the roller 22, and land upon the side table 56, the movement of the apron 51 being toward the left in its upper reach.

40 If desirable, a small sprocket 57 may be mounted on the shaft 55 and driven by a large sprocket 58 and chain 59, the large sprocket being on the shaft of the large roller, as shown.

45 Mounted on the upper edge of the box spaced from the standards 25 oppositely from the large roller there is a crank shaft 60 carrying a gear 61 meshed with the gear 18. Outwardly of this shaft there is a roller 50 61', mounted upon the shaft 62 which suspends a dasher board 63, connected by the link 64 to the crank 65 of the shaft 60, before mentioned. A shirt table piece 66 is mounted slidably upon the box outwardly 60 of the roller 61 and is provided with a pivoted board 67 similar to and opposed to the one 63, the adjacent faces of these boards being corrugated. The lower end of the board 67 is resiliently held against oscillatory movement by a suitable spring 68 rest-

ing against the board and mounted on the end of the box 10. The mounting of the roller 61' consists of a suitably slotted guide block 69, in which a slide bearing 70 is mounted, carrying the roller shaft, a spring 71 being engaged in the inner end of the slot to hold the roller yieldably at the outer limit of its movement. The upper end of the board 67 is concaved so as to snugly fit against the roller when pressed inwardly 75 under sliding movement of the table 66. The sliding movement of the table 66 is controlled by the foot pedal 72, pivoted on the supporting frame work of the box 10 connected by any suitable operative connections 80 with the table, for inward movement thereof. In the present case, a cable 73 at each side of the device is connected to the under side of the table within the box 10, from whence it extends outwardly through an opening 75 in the side of the box around a suitable pulley 74, shown in Fig. 1. From here the cable is carried outwardly again and over a suitable pulley 76, where it is connected through the agency of a spring 77 and rod 85 90 to the foot pedal.

95 It should be noted that the upper portion 80 of each arm 35 has an intermediate offset portion 81, whereby to accommodate diagonally arranged guides 82 secured to the box 10 at each side adjacent the upper edge, each guide having a sliding bearing 83, adjustable by a screw 84 projected above the box. The bearings 83 support a supplementary starch expressing roller 85, which may be 100 caused to press with considerable force against the large roller 22 adjacent the top of the box, the guideway 82 being disposed at an acute angle to the periphery of the roller 22 so that the maximum pressure is 105 attained with a minimum of effort on the part of the operator. Sufficient play of the shaft of the roller 85 must of course be permitted in the arms 35 to prevent interference with their separate adjustment. 110

115 In operation, the box being filled to the proper depth with fluid starch, and power being communicated through the belt 16, the roller 22 will rotate in a counter clockwise direction as viewed in Fig. 4. Collars and cuffs may then be fed to the throat 44, and will be carried beneath the roller in close contact with the apron 43 which will have previously circulated through and taken up a large quantity of starch. As the rollers 41 are encountered the starch will be pressed through the fabric of the collars and cuffs and surplusage removed. This removal of starch may be made more thorough by adjustment of the roller 85, although the pressure of the rollers 41 may be modulated by the adjusting screw 37. The collars and cuffs are carried past the roller 22 upwardly by the apron and tapes, and discharged upon the delivery apron 51, by which they are 120 125 130

carried to the left side of the machine and dropped upon the table 56. In case the cuffs and collars tend to adhere to the apron, a series of spring fingers 87 may be mounted 5 between the outer brackets 45 and 46, whereby the adhering articles are loosened and caused to fall upon the delivery apron. The delivered cuffs and collars may be brushed from the table 56 into a receptacle by the 10 same operator who feeds the machine, or a receptacle, such as a basket, may be set upon the table to receive the articles direct.

For starching shirts, the table 66 is drawn outwardly, presenting a space between the 15 boards 63 and 67 before the roller 61, through which the garments are dropped as far as desired. The table 66 is then pressed inwardly with the necessary force, which may be readily accomplished by a slight 20 pressure on the pedal 72 and the garment withdrawn while pressure is maintained on the pedal, the upper part of the board 67 and the roller 61 coöperating to express the surplus starch.

25 For convenience in cleaning out the starch box, there may be provided at each side a lever 90, as shown in Fig. 5 pivoted intermediately of its length upon the end of the shaft 23, the lever extending inwardly 30 and having a recessed inner end 91 receiving the shaft 21 therein, whereby when the bearings of the shaft are loosened, the levers may be depressed at their outer ends to lift the rollers 22 out of the box, enabling 35 ready access to the interior thereof.

It will be noted that the connections with the transverse conveyer are such as to make it operate more rapidly than the apron belt, whereby articles are kept separated and delivered one at a time under the customary 40 method of feeding.

What is claimed:

1. A starching machine of the class described, comprising a starch box, a conveyer 45 for collars and cuffs having a path leading from one end of the box downwardly and then upwardly, thence outwardly toward said end of the box for discharge, and a transverse conveyer mounted to receive articles from the first conveyer extending laterally of the machine, and operative connections for the said conveyers.

2. A starching machine comprising a starch box, a feed table adjacent one side 55 thereof, supports at two sides of the box spaced from said table and including extensions toward the table, a train of rollers mounted in the box and on the said supports including one at the outer end and two 60 at the base of said extension, one below and forwardly of the other, an apron belt carried by said roller train to circulate at the outer sides of all of the rollers except the last named one, said belt being engaged inwardly of said last named roller, at least

one roller located within the train in the box, and receiving said apron thereunder, endless tapes engaged therearound and around said last named roller on the supports, a transversely disposed horizontal 70 conveyer carried by the said extensions having its inner side closely adjacent said last named roller on the supports, and operative connections for the conveyer and apron.

3. A starching machine comprising a starch box, a large transverse roller mounted revolvably therein, a small fixed roller closely adjacent and parallel to the first named roller, a pivoted frame in the box at each side, a plurality of rollers carried thereby below and rearwardly of the large roller, standards fixed over the box, upper and lower rollers carried by the standards the lower one having its rearmost periphery spaced forwardly of the like part of the upper roller, an extension on each of the standards projected forwardly intermediately of said rollers on the standards, a roller at the outer ends of the extensions, an endless apron engaged under said large roller and outwardly of the other rollers in the box, the upper roller on said standards and the roller at the outer ends of the extensions and inwardly of the lower roller on the standards, endless tapes engaged around said last 95 named roller and the large roller, a transverse horizontal conveyer carried beneath said extensions and having its inner edge closely adjacent said lower roller on the standards, means for adjusting said pivotal frame, separate means for tightening the endless apron member, means to operate certain of the rollers and operative connections between certain of the rollers and the transverse conveyer.

4. In a device of the class described, conveyer devices including a roller having a fixed axis and a fibrous apron operative to convey fabrics between the roller and apron, guide devices arranged in a plane convergent to the periphery of said first named roller, a sliding bearing in each guide device, a roller journaled in the bearings and means to move the bearings in the guide devices said guide devices being so positioned 110 that the last named roller is in engagement with the first named roller adjacent the inner limit of its movement.

5. In a machine of the class described, a conveyer belt, means to support the belt in 115 a tortuous path including an ascending reach and a reach leading forwardly at an angle to the first named reach, a transverse delivery element beneath said last named reach, means to hold material upon the belt 120 over a part of its path not including the last named reach, and operative connections for the mechanism.

6. In an apparatus of the class described 130 a conveyer element movable to deliver mate-

rial in a given direction and a second conveyer arranged to receive from the first and movable to convey material laterally from the first conveyer, and operative means to operate the conveyer including connections to cause the last named conveyer to operate more rapidly than the first named conveyer.

In testimony whereof I have hereunto set my hand in presence of two subscribing witnesses.

OLOF FROBERG.
